UNITED STATES PATENT OFFICE

2,576,702

VELOCITY MODULATION ELECTRON
DISCHARGE DEVICEWilliam J. Scott, Rugby, England, assignor to
General Electric Company, a corporation of
New YorkApplication December 27, 1946, Serial No. 718,797
In Great Britain December 22, 1941Section 1, Public Law 690, August 8, 1946
Patent expires December 22, 1961

5 Claims. (Cl. 315—5)

1

My invention relates to electron discharge devices of the velocity modulation type employing one or more cavity resonators, and is particularly concerned with such devices in which at least one of the walls of the resonator is flexible and adjustable relative to an opposed wall to vary the resonant frequency of the cavity.

Hitherto the dimensions of the resonating chamber have usually been such that the diameter of the glass portions of the envelope necessary to support and seal the electron gun and electron collecting or reflecting electrode to the cavity resonator is less than that of the resonator. The glass portions have thus been ring sealed to opposite faces of the resonator which forms a part of the evacuated envelope of the device. With an increase in the operating frequency at which the device operates, however, the size of the resonator becomes such that it may readily be included within the envelope. My invention relates to an improved structure for velocity modulation devices and particularly to such devices for higher operating frequencies which may be more readily manufactured with the required accuracy.

It is the object of my invention to provide a simplified construction for devices of the above type which facilitates their manufacture and assembly.

It is another object of my invention to provide an improved tunable resonator for velocity modulation devices.

According to one illustrated embodiment of my invention, one wall of the resonating chamber is made rigid and is rigidly mounted with relation to a stem which also supports the electron gun or cathode structure while the other wall of the chamber is made resilient and is connected with a resilient wall portion of the envelope so that the dimensions of the chamber may be varied. The reflecting electrode is also supported by a lead sealed through the stem to provide a single-ended construction of the device and to render the position of the reflecting electrode independent of the flexible wall.

My invention will be better understood by reference to the following description taken in connection with the accompanying drawing and its scope will be pointed out in the appended claims. In the drawing, Fig. 1 is an elevational view in section of an electric discharge device embodying my invention and Fig. 2 is an elevational view in section of a modification.

Referring now to Fig. 1 of the drawing, the member 1 forming a rigid wall of a resonating chamber 2 is located wholly within the envelope

2

of the device. The envelope includes a stem 3 attached to a glass wall portion 4 to which is sealed a metal wall portion 5 terminating at its end remote from the stem 3 in a resilient wall portion 6. These three parts are sealed together so as to form a vacuum-tight envelope, the glass portion 4 and the metal portion 5 being of such compositions that their thermal expansion characteristics are matched to insure a substantially strain-free seal between them.

The member 1 consists of a relatively heavy disc of metal, such as copper, which is recessed to provide part of the resonating chamber 2. The resonating chamber 2 is completed by a resilient wall portion 8 secured to the open face of the member 1. The resonator is supported from the stem 3 by means of rigid leads 7, which are joined to the member 1 and are sealed to the stem 3. A cathode or electron gun 9 is also supported on the stem 3 and positioned to direct an electron beam through aligned apertures formed in the walls of the resonating chamber 2. As illustrated, the rigid member 1 is provided with an inwardly directed conical flange 1' which terminates just short of the apertured resilient wall to define a gap 2' across which the beam of electron passes. A reflector electrode 10 positioned beyond the wall 8 is supported from the stem 3 upon a relatively rigid member 11 which is offset to accommodate the resonator. The resonator may be slotted as illustrated at 12 to receive the member 11.

Preferably the rigid part 1 of the resonator fits closely into the metal portion 5 of the envelope and its thermal contact with the envelope may be improved by the known method of melting pure tin during the exhaust into the minute space so formed.

Secured to the resilient wall portion 6 of the envelope is a member 13 having a threaded shank 14 extending through the resilient wall of the envelope in a vacuum-tight manner. The member 13 is secured at its lower end 15 to the resilient wall portion 8 of the resonating chamber 2 and owing to the ability of the resilient wall portion 6 of the envelope to deflect, it is possible by deflecting the resilient wall 8 to alter the width of the gap 2' across which the electron beam is projected and consequently to alter the resonant frequency of the cavity. This deflection may be effected with considerable accuracy in accordance with the invention by means of a differential screw supported in a fixed part external to the envelope and mechanically connected with the screw-threaded shank 14 of the member 13.

As illustrated in the drawing, a rigid transverse member 16 is provided with an opening for the reception of the envelope 5 and its suitably bonded thereto as by welding. A similar rigid member 17 is secured to the flexible wall 6 and through the member 13 is directly connected with the flexible wall 8 of the resonator. Member 16 carries a pair of vertical rigid arms 18 which are interconnected at their upper ends by a rigid transverse member 19. In a similar way the member 17 carries a pair of vertically extending arms 20 which are interconnected at their upper ends by a transverse member 21. Transverse members 19 and 21 are interconnected by a differential screw mechanism including a thumb screw 22 having an external thread received in a threaded opening in the transverse member 19 and having an internal thread for receiving a threaded stud 23 which is rigidly secured to the transverse member 21. The external and internal threads of the screw 22 are of the same hand but of different pitch so that rotation of the screw 22 effects relative movement of the members 19 and 21 in accordance with the difference in pitch of the two threads. In order to minimize the effect of backlash in the threads, a compression spring 24 is interposed between the members 19 and 21. It is well understood that resonators of the type provided by the rigid member 1 and flexible wall 8 tend to change dimensions with changes in operating temperature. In order to compensate for terminal changes and maintain the operating frequency substantially constant, the rigid portions 18 and 20 may be formed respectively of materials having different temperature coefficients of expansion. By a proper selection of the materials and the dimensions of the parts employed, it will be apparent that automatic compensation for temperature changes are effected. Iron and brass may be employed as suitable materials for the parts 18 and 20.

High frequency energy may be extracted from the resonator by means of a section of concentric transmission line including an inner conductor 25 and an outer conductor 26. The inner conductor is coupled to the interior of the resonator by means of a suitable coupling loop 27 and the end of the transmission line section is closed by a body of glass 28 sealed to the outer conductor and enclosing the end of the inner conductor.

It will also be appreciated that suitable lead-in conductors connected with the various electrodes may be sealed in the stem 3 and connected with the contact prongs of a conventional tube base (not shown).

The discharge device described above is a reflexed type velocity modulation oscillator, and its operation is believed to be well understood. Electrons emitted by the cathode structure 9 pass through the aligned aperture in the resonator 2. As it is assumed that a high frequency voltage appears across the gap 2', the beam is velocity modulated. The electrons of the seal are then resealed by the reflex electrode 10 which is operated at a suitable positive potential, and returned through the resonator in proper phase returns to reinforce the high frequency oscillation which produced the modulation of the beam. In this way substantially high frequency voltages are built up across the gap and high frequency energy may be extracted from the cavity by means of the transmission line including conductors 25 and 26.

In Fig. 2 I have shown a modification of my invention which is in general similar to that shown in Fig. 1 and corresponding parts have been designated by the same reference numerals. In Fig. 2 the rigid body 1 forming part of the resonator is of larger diameter than the body of the envelope and extends beyond the envelope wall as illustrated.

The body 1 is received between the opposed flanges 29 of envelope sections 30 and 31 which correspond to the rigid envelope member 5 of Fig. 1. In the modification shown in Fig. 2, the outer conductor of the transmission line is provided by the defining wall of a cylindrical recess provided in the resonator body 1. The inner conductor of the transmission line is sealed through the glass body 28 so that the output may be conductively connected with a further section of concentric transmission line.

It will be apparent from the foregoing description that my invention provides a tube structure which is particularly well adapted for the manufacture of very high frequency devices and which provides for the ready adjustment of the operating frequency. The construction also provides a single-ended discharge device in which the reflecting electrode is supported independently of the movable wall of the resonator.

While I have described and illustrated a particular embodiment of my invention, it will be obvious to those skilled in the art that changes and modifications may be made without departing from my invention in its broader aspects and I therefore aim in the appended claims to cover all such changes and modifications as fall within the true spirit and scope of my invention.

What I claim as new and desire to secure by Letters Patent of the United States is:

1. An electric discharge device of the velocity modulation type including an envelope, a cavity resonator including a rigid wall part supported in fixed relation to said envelope and a flexible wall secured to said rigid wall and cooperating therewith to define the resonator, a cathode supported on the side of said resonator opposite said flexible wall, a reflector electrode on the opposite side of said resonator and supported in fixed relation to said envelope, said envelope including a flexible wall, and mechanical means connecting said flexible wall of said resonator with said flexible wall of said envelope for producing movement of said flexible wall with respect to said rigid wall.

2. An electric discharge device of the velocity modulation type including an envelope, a cavity resonator including a rigid wall part supported in fixed relation within said envelope and a flexible wall secured to said rigid wall and cooperating therewith to define the resonator, a cathode supported on one side of said resonator from one end of said envelope, a reflector electrode on the opposite side of said resonator and supported in fixed relation to said envelope, and mechanical means connecting said flexible wall with a flexible wall portion provided in the opposite end of said envelope for producing movement of said flexible wall of said resonator with respect to said rigid wall thereof.

3. An electric discharge device of the velocity modulation type including an envelope, a cavity resonator supported within the envelope and including opposed walls having aligned entrance and exit openings respectively, the wall in which said exit opening is provided being flexible, a cathode supported in fixed relation with respect to

said envelope on the side of said resonator nearer the entrance opening for providing a stream of electrons which pass through the entrance and exit openings of said resonator, a reflecting electrode supported in fixed relation with respect to said envelope on the side of said resonator nearer said exit opening and in alignment with said entrance and exit openings, means joined to the flexible wall of said resonator adjacent said exit opening and means interconnecting said last-mentioned means and a rigid portion of said envelope for producing movement of the flexible wall of said resonator with respect to the opposite wall thereof.

4. An electric discharge device of the velocity modulation type including an envelope, a cavity resonator supported wholly within the envelope and including aligned entrance and exit openings formed in the walls thereof, the wall around said exit opening being flexible, a cathode supported in fixed relation with respect to said envelope on the side of said resonator nearer the entrance opening for providing a stream of electrons which pass through the entrance and exit openings of said resonator, a reflecting electrode supported in fixed relation with respect to said envelope on the side of said resonator nearer said exit opening and in alignment with said entrance and exit openings, a tubular member joined to the flexible wall of said resonator adjacent said exit opening and recessed to receive said reflecting electrode and means interconnecting said last-mentioned means and a rigid portion of said envelope for producing movement of the flexible wall of said resonator with respect to the opposite wall thereof.

5. An electric discharge device of the velocity modulation type including an envelope, a cavity resonator supported within the envelope and including aligned entrance and exit openings formed in the walls thereof, the wall around said exit opening being flexible, a cathode supported in fixed relation with respect to said envelope on the side of said resonator nearer the entrance opening for providing a stream of electrons which pass through the entrance and exit openings of said resonator, a reflecting electrode supported in fixed relation with respect to said envelope on the side of said resonator nearer said exit opening and in alignment with said entrance and exit openings by means including a conductor extending around said resonator, means joined to the wall of said resonator adjacent said exit opening and means interconnecting said last-mentioned means and a rigid portion of said envelope for producing movement of the flexible wall of said resonator with respect to the opposite wall thereof.

WILLIAM J. SCOTT.
